PLANT PROTECTOR

Hamilton C. Chase and Philip H. Sanford,
Los Angeles, Calif.

Application November 24, 1933, Serial No. 699,538

9 Claims. (Cl. 47—28)

This invention relates to plant protectors which are adapted to be set over seeded portions and growing plants to protect them from the inclemencies of the weather and which will shield the plant from light rays of too intensive magnitude for their most effective growth. It is common practice to employ paper protectors for this purpose and to form the protectors of translucent paper known as "plant glass". Such protector should be of a shape such as to readily shed water, permit droplets collecting on the inner surface to run down the walls; should be of a shape so as not to crowd the plant at its upper portions as it enlarges during growth; should be self contained, maintain its shape during handling and economical to construct.

The object of this invention is to provide a plant protector having any or all of the last mentioned desiderata.

20 This object is accomplished by the plant protector illustrated in the accompanying drawing, in which:—

Fig. 1 is a perspective view of a completed protector; Fig. 2 shows a face view of three paper blanks in initial assembled position for constructing a protector; and Fig. 3 is a sectional view of a fragment as seen on the line 2—2 of Fig. 1.

Referring more particularly to Fig. 1, it will be noted that the protector is of marquee tent form, having a hexagonal body portion and a dome. Earth anchor tabs outstand from the body at the base.

For the hexagonal form of protector disclosed, blanks are cut from paper such as "plant glass", and in the form shown in Fig. 2. The outline of the blanks is such as to provide a symmetrical shape wherein there are flaps 5 joined by a constricted waist 6. The flaps 5 are in general of gable form having hips 7. The portions within 40 the hips are designed to form the dome like roof, and the outer portions of the flaps are provided for side walls. It will be noted that the blanks are provided with gummed strip belts 8 and 9 cemented thereto. Belts 8 extend transversely 45 between hips, and belts 9 range transversely across the flaps near their outer ends. These belts are placed in position before the blanks are cut from the stock.

The blanks positioned in cruciform relation as shown in Fig. 1 are placed over a forming block and brought down over the sides with side edges of adjacent blanks meeting. The blanks are creased at longitudinal edges of belts 8 to form roof eaves. They are also creased at longitudinal 55 edges of belts 9 and turned outwardly to form

earth anchor tabs 10. Gummed strips 11 are creased along their medial longitudinal axes and cemented over the meeting edges of the blanks forming a complete protector.

The "plant glass" paper is translucent and comparatively thin. The creased strips of V cross sections provide reinforcement studs and together with the belts form a frame work for the paper, such that the tent is form retentive and will not collapse under its own weight or that encountered in handling. The entire structure is light in weight. The apex 12 formed by the overlapping waists adds to the stability of the structure against collapse.

In the use of the protector, it is placed over a seeded part of the soil or a plant. The earth or any other suitable loose material is piled over the earth anchor tabs 10. The protector forms a housing to shield the plant or seeded portion against rain, snow, wind, and hail, to keep the temperature within fairly constant and to absorb some of the light. Obviously, water which impinges or collects on the outside is readily shed. Also water collecting on the inside will follow the walls to the ground. The upper portion of the protector is not constricted so as to crowd the growing plant. Protectors made in accordance with our invention are economical to manufacture and use.

What we claim is:—

1. A plant protector of tent form comprising a plurality of like paper blanks, each of said blanks being symmetrical and having flap portions joined by a medial restricted waist, said blanks being assembled in cruciform relation overlapping at their waists to provide an apex and having their adjacent marginal edges meeting one another, and reinforcing fastening strips extending along the meeting edges of said flaps, overlapping the marginal edges thereof and cemented thereto, said strips being sharply creased longitudinally to provide V cross sections.

2. A plant protector of tent form comprising a plurality of like paper blanks, each of said blanks being symmetrical and having flap portions joined by a medial constricted waist, said blanks being assembled in cruciform relation overlapping at their waists to provide an apex and having their adjacent marginal edges meeting one another for the major portions of their extents, the outer ends of said blanks being free and creased transversely to provide outwardly directed earth anchor tabs; and reinforcing and fastening strips extending along the meeting edges of said flaps, overlapping the marginal edges thereof and ce-

- mented thereto, said strips being sharply creased longitudinally to provide V cross sections.
3. A plant protector of marquee tent form comprising a plurality of like paper blanks, each of said blanks being symmetrical and having flap portions of gable form joined by a medial constricted waist, said blanks being assembled in cruciform relation overlapping at their waists to provide an apex and having their adjacent marginal edges meeting one another, said blanks being creased transversely between hips; and reinforcing and fastening strips extending along the meeting edges of said flaps, overlapping the marginal edges thereof and cemented thereto, said strips being sharply creased longitudinally to provide V cross sections.
4. A plant protector of marquee tent form comprising a plurality of like paper blanks, each of said blanks being symmetrical and having flap portions of gable form joined by a medial constricted waist, said blanks being assembled in cruciform relation overlapping at their waists to provide an apex and having their adjacent marginal edges meeting one another, said blanks being creased transversely between hips; reinforcing and fastening strips extending along the meeting edges of said flaps, overlapping the marginal edges thereof and cemented thereto, and reinforcing belts ranging along and extending between the hips and cemented thereto, said strips being sharply creased longitudinally to provide V cross sections.
5. A plant protector of marquee tent form comprising a plurality of like paper blanks, each of said blanks being symmetrical and having flap portions of gable form joined by a medial constricted waist, said blanks being assembled in cruciform relation overlapping at their waists to provide an apex and having their adjacent marginal edges meeting one another for the major portions of their extents, said blanks being creased transversely between hips, the outer ends of said blanks being free and creased transversely to provide outwardly directed earth anchor tabs; and reinforcing and fastening strips extending along the meeting edges of said flaps, overlapping the marginal edges thereof and cemented thereto, said strips being sharply creased longitudinally to provide V cross sections.
6. A plant protector of marquee tent form comprising a plurality of like paper blanks, each of said blanks being symmetrical and having flap portions of gable form joined by a medial constricted waist, said blanks being assembled in cruciform relation overlapping at their waists to provide an apex and having their adjacent marginal edges meeting one another for the major portions of their extents, said blanks being creased transversely between hips, the outer ends of said blanks being free and creased transversely to provide outwardly directed earth anchor tabs; reinforcing and fastening strips extending along the meeting edges of said flaps, overlapping the marginal edges thereof and cemented thereto, and reinforcing belts ranging along the creased portions at the anchor tabs and cemented thereto, said strips being sharply creased longitudinally to provide V cross sections.
7. A plant protector of tent form comprising a plurality of like paper blanks, each of said blanks being symmetrical and having flap portions joined by a medial constricted waist, said blanks being assembled in cruciform relation overlapping at their waists to provide an apex and having their adjacent marginal edges meeting one another for the major portions of their extents, the outer ends of said blanks being free and creased transversely to provide outwardly directed earth anchor tabs; reinforcing and fastening strips extending along the meeting edges of said flaps, overlapping the marginal edges thereof and cemented thereto, and reinforcing belts ranging along the creased portions at the anchor tabs and cemented thereto, said strips being sharply creased longitudinally to provide V cross sections.
8. A plant protector of marquee tent form comprising a plurality of like paper blanks, each of said blanks being symmetrical and having flap portions of gable form joined by a medial constricted waist, said blanks being assembled in cruciform relation overlapping at their waists to provide an apex and having their adjacent marginal edges meeting one another for the major portions of their extents, said blanks being creased transversely between hips, the outer ends of said blanks being free and creased transversely to provide outwardly directed earth anchor tabs; reinforcing and fastening strips extending along the meeting edges of said flaps, overlapping the marginal edges thereof and cemented thereto, and reinforcing belts ranging along the creased portions at the anchor tabs and cemented thereto, said strips being sharply creased longitudinally to provide V cross sections.
9. A plant protector of marquee tent form comprising a plurality of like paper blanks, each of said blanks being symmetrical and having flap portions of gable form joined by a medial constricted waist, said blanks being assembled in cruciform relation overlapping at their waists to provide an apex and having their adjacent marginal edges meeting one another for the major portions of their extents, said blanks being creased transversely between hips, the outer ends of said blanks being free and creased transversely to provide outwardly directed earth anchor tabs; reinforcing and fastening strips extending along the meeting edges of said flaps, overlapping the marginal edges thereof and cemented thereto, and reinforcing belts ranging along the creased portions at the hips and cemented thereto, and reinforcing belts ranging along the creased portions at the anchor tabs and cemented thereto, said strips being sharply creased longitudinally to provide V cross sections.
